UNITED STATES PATENT OFFICE.

WILLIAM E. WINE, OF TOLEDO, OHIO.

CAR-DOOR MECHANISM.

Application filed October 10, 1922. Serial No. 593,525.

This invention relates to a drop door arrangement for railway cars and has as one of its principal objects to provide a simple and economical form of door-supporting mechanism wherein the door may be held in a partly or in a completely closed position, and also to afford a door device wherein the door supporting mechanism may be actuated to force the door from a partly closed 10 to a fully closed position. Other objects are to provide a door device of sturdy construction and one that may be operated by inexperienced and unskilled workmen.

With such general objects in view, the 15 invention consists of the construction, combination and arrangement of parts as will be herein described and particularly claimed.

In the accompanying drawings, which 20 show a preferred embodiment of the invention, Figure 1 is a side elevational view of a portion of a car body, together with a hinged door applied thereto and a door-supporting mechanism constructed in accordance with the principles of the present 25 invention. Figure 2 is a transverse vertical sectional view through a portion of the car and one of the doors, taken approximately on the line 2—2 of Figure 1, the door being 30 shown in fully closed position. Figure 3 is a fragmentary view similar to Figure 2, but showing the door in partly closed position.

Referring to these drawings, the side of 35 the car is denoted by the numeral 1. This in the present embodiment consists of a steel plate, which has an angle iron stiffening member 2 secured along the lower edge thereof by means of rivets 3. The car may 40 have the customary longitudinal center sill arrangement 4 of channel and plate construction, and a covering plank 5 may extend longitudinally of the car over the center sill. Cross bearers such as 6 extending 45 from side to side of the car may be employed.

Hinge members 7 are shown as attached 50 to the center sill by means of rivets 8, and to these fixed car body hinges are pivoted door hinges 9. The door in the present embodiment is arranged to swing from alongside of the center sill 4 so that its free edge when in closed position extends along the side of the car, the axes of the hinge pintles 55 26 being disposed longitudinally of the car and parallel with the center sill 4. The

door hinges are shown as composed of angle irons 10, together with hinge clips such as 11, the latter being secured to the angles 10 as by means of rivets 12. Two such 60 hinges may be used for each door, and the door planking 13 may be positioned upon the tops of the angle irons 10, bolts 14 being employed to secure the door planking to the top legs of the angle irons 10. The door 65 is arranged to close beneath the horizontal leg of the angle iron 2, and the outermost ends of the angle irons 10 are arranged to extend outwardly beyond the edge of the door and beyond the side of the car body 70 and beneath the car side plate 1, thus constituting door-supporting arms.

In the present embodiment, a door-supporting mechanism is provided for cooperating with each of the angle irons 10, each 75 of said mechanisms embodying a bracket 15 which is secured to the outer face of the car side by means of rivets 16. To each of these brackets 15 is pivoted a sling or loop 17 which is arranged to swing outwardly 80 from the car side to release the door and inwardly or toward the center of the car to support the door in closed position. These slings are pivoted within suitable openings 18 in the brackets 15. A casting 19 secured to the top face of each angle iron 10 has its upper portion formed as an inclined plane 85 adapted to contact the lower portions of the slings, or members 20 carried therefrom, to cause the slings to swing outwardly when 90 the door is lifted, thus enabling the slings to drop by gravity into supporting positions beneath the angle irons 10.

Each sling has mounted upon its lowermost portion a rotatable cam or latch member 20 which is adapted to seat beneath the angle iron when in supporting position. This latch or cam 20 is arranged so that it can be moved or rotated upon the sling to thereby support the door in a partially 100 closed or fully closed position. To this end, the cam is formed so that its axis of rotation is less distant from the preliminary supporting surface 21 than it is from the final supporting surface thereof, such as 22. An 105 extension 23 may be and preferably is formed at a convenient place upon this latch to assist in forcing it into or out of engagement with the door angle, or to move it from one position of engagement to another.

The contour of the outermost end of each

- angle 10 is formed to co-operate with the contacting surface of the cam 20, and the angle 10 may also have applied to its outermost end an adapter casting, such as 24, 5 to strengthen the end of the angle and to increase the bearing surface for the cam 20. Rivets 25 may be utilized for attaching this casting to the angle 10, and also for tying the casting 19 thereto.
- 10 In operation, the door is lifted by hand to the position shown in Figure 3, when the end of the angle may seat upon the surface 21 of the cam 20, thereby supporting the door in a partly closed position. By now 15 rotating the cam in a counter-clockwise direction, as it appears in Figure 3 of the drawings, the door will be forced to the fully closed position as shown in Figure 2 by the eccentric action of this cam in its 20 co-operation with the bearing surface of the angle iron 10 and the bracket 24.
- The contours of the cam and of the contacting surface of the angle iron are preferably so developed that when the cam 20 25 is rotated to the fully closed position of the door, as shown in Figure 2, it will be in a position slightly beyond one in which the effect of the load will be to release the door, or in other words it is carried slightly beyond the dead center, so that the weight of the door will not tend to reverse the rotation of the cam.
- I have thus described a preferred embodiment of my invention. Other embodiments 35 are contemplated within the scope of the appended claims without departing from the spirit thereof.
- What is claimed is:
1. In a car door mechanism, a drop door 40 hinged to the car body and having an arm extending outward beyond one edge thereof, a door-supporting member pivoted to the car body, and a door-engaging latch movably mounted on the said door-supporting member at a point which is below the door when the latter is in closed position, said latch being adapted when in one position to engage the said arm to support the door in partly closed position, and being 45 adapted when moved to another position upon the said door-supporting member to cause the door to be raised to a fully closed position.
  2. In a car door mechanism, a drop door 55 hinged to the car body and having an arm extending outward beyond one edge thereof, and a door-supporting sling pivoted to the car body and adapted to swing over the end of the said arm, the said sling being provided with a rotatable cam adapted to en-
- gage said arm, and the surface of the said cam of the coengaging portion of the said arm being so formed that in one position of the cam the door will be supported in partly closed position and that rotation of 65 the cam to another position will cause a lifting of the door.
3. In a car door mechanism, a drop door hinged to the car body and having a bracket 70 affixed thereto near the free edge of the door, a bracket affixed to the car body near the said door bracket when the door is in closed position, and a link or loop pivoted upon one bracket and engageable with the other bracket and adapted to support the door in 75 partly closed or fully closed position, there being a rotatable eccentric member so interposed between the link and said bracket affixed to the door as to cause upon rotation thereof, lifting of the door and locking of 80 the said link in supporting engagement between the two brackets.
4. In car door mechanism, a drop door hinged to the car body, an arm carried by 85 said door and extending outwardly beyond an edge of the latter, a door supporting member movably mounted on the car body and extending downwardly so as to overlap said arm when said door is in closed position, and a cam rotatably mounted on said door 90 supporting member and adapted to engage said arm.
5. In car door mechanism, a drop door hinged to the car body, and means for supporting said door in closed position, said 95 means involving a member pivoted to said car body and extending on opposite sides of the plane of said door, and a cam rotatably mounted upon said pivoted member and adapted to be positioned between the 100 latter and said door.
6. In car door mechanism, a drop door hinged to the car body, an arm carried by 105 said door and projecting beyond an edge thereof, a pivoted door supporting member carried by said car body and adapted to extend beneath said arm so as to support said door, and means whereby said arm while supported by said pivoted member may be caused to move toward the pivot 110 point of the latter, said means being movably mounted upon said pivoted supporting member and being adapted to occupy a position between said supporting member and said arm when the door is supported against 115 opening movement.

In testimony whereof I affix my signature.

WILLIAM E. WINE.
